UNITED STATES PATENT OFFICE.

CAROLINE E. G. WAGNER, OF TORONTO, CANADA.

COLLAR MEASURER AND FITTER.

No. 800,696.

Specification of Letters Patent.

Patented Oct. 3, 1905.

Application filed November 14, 1904. Serial No. 232,661.

To all whom it may concern:

Be it known that I, CAROLINE EMILY GER-
RUDE WAGNER, of the city of Toronto, in
the county of York, in the Province of On-
tario, Canada, have invented certain new
and useful Improvements in Collar Measurers
and Fitters, of which the following is the
specification.

My invention relates to improvements in
collar measurers and fitters; and the object
of the invention is to devise a cheap and
efficient adjustable device of this class
whereby ladies' collars or ribbons may be
accurately measured, fitted, and finished;
and it consists, essentially, of a strip of metal
of arc-shape form provided at one end with
two sets of slots, one near the top and one
near the bottom edge, and at the opposite
end with two tongues having inwardly-bent
ends designed to engage the aforesaid slots
when the strip of metal is bent up into the
collar form, the measurer being otherwise
constructed and arranged in detail as here-
inafter more particularly explained.

Figure 1 is a perspective view of my collar
measurer and fitter, showing it closed and in
the position in which it will be fitted around
the neck. Fig. 2 is a perspective view of
the collar open.

In the drawings like characters of refer-
ence indicate corresponding parts in each
figure.

A is a metal plate, preferably spring metal,
which is provided near one end with one set
of slots a , preferably a quarter of an inch
from center to center and located near the
upper edge, and another set of slots a' near
the bottom edge and preferably the same
distance apart and located opposite the
aforesaid slot each to each. The distances
apart of the slots are indicated by the nu-
merals "12," "13," "14," and "15," &c., if
necessary, such numbers indicating inches.

a^2 and a^3 are tongues provided with in-
ward bends, such inward bends being de-
signed to be brought through the top and
bottom slots, respectively, so as to get the
set and fit of the collar, such tongues locking
the ends in position.

a^4 is a loop stamped or formed out of the
collar intermediate of its length and designed

to receive a hook or other device for holding
down the back of a collar or ribbon while it
is being fitted.

2, 3, 4, 5, and 6 are rows of holes which are 55
designed to be utilized while embroidering a
collar which is previously fitted onto the
plate. The edge holes 2 and 6 may be
utilized for basting the collar in position.

The measurer and fitter may be utilized 60
in various ways for measuring, fitting, and
finishing collars, stocks, or ribbons for the
neck.

Although I show my device as particularly
applicable to collars, it will of course be 65
understood that it may be with equal facility
applied to belts or cuffs without departing
from the spirit of my invention.

In using my invention I take the plate
and place it around the neck in the form 70
shown in Fig. 1, placing the lower tongue in a
slot, so that the device will fit the neck at
the bottom, and the upper tongue in an
upper slot, so as to fit the neck at the top,
and by this means I get a perfect fit. I then 75
disengage the tongues and unclasp the de-
vice from the neck and fit it together into
the same slots again and form my collar on
my device in such form. I then rip it off
and put it together in any suitable way, de- 80
pending whether it is a permanent collar or
stock or ribbon.

What I claim as my invention is—

1. A measurer and fitter for collars and
the like comprising an arc-shaped plate of 85
metal provided toward one end with two
sets of aligned slots, one at the top and one at
the bottom and at the opposite end with pro-
jecting tongues having inwardly-bent ends
designed to fit into the aforesaid slots as and 90
for the purpose specified.

2. A measurer and fitter for collars and
the like comprising an arc-shaped plate of
metal provided toward one end with two
sets of aligned slots, one at the top and one at 95
the bottom having the size-measurement
indexes opposite them and at the opposite
end with projecting tongues having inwardly-
bent ends designed to fit into the aforesaid
slots as and for the purpose specified. 100

3. A measurer and fitter for collars and
the like comprising an arc-shaped plate of

metal provided toward one end with two sets of alined slots, one at the top and one at the bottom having the size - measurement indexes opposite them and at the opposite 5 end with projecting tongues having inwardly-bent ends designed to fit into the aforesaid slots, and a metal loop struck out of the

plate intermediate of its length and near the bottom edge as and for the purpose specified.

CAROLINE E. G. WAGNER.
